UNITED STATES PATENT OFFICE.

CHARLES A. JUENGST, OF CROTON FALLS, NEW YORK, ASSIGNOR TO AMERICAN ASSEMBLING MACHINE COMPANY, A CORPORATION OF DELAWARE.

GROOVING DEVICE

1,280,753.

Specification of Letters Patent. Patented Oct. 8, 1918.

Application filed October 26, 1916. Serial No. 127,787.

To all whom it may concern:

Be it known that I, CHARLES A. JUENGST, a citizen of the United States, and a resident of Croton Falls, in the county of Westchester and State of New York, have invented certain new and useful Improvements in Grooving Devices, of which the following is a specification.

This invention relates generally to groove cutting devices and in particular to devices for grooving the backs of books preliminary to the application of covers thereto.

In the art of book binding frequent use is made of book covering machines in which an endless conveyer is arranged to carry the books consecutively from one operating means to another in order to have performed thereon the desired number of operations found necessary in applying a cover to a book. One of the operations thus performed in machines of this character has been the roughening of the book back preparatory to the application of adhesive material thereto in order to provide a greater area of surface to which the adhesive can adhere and thereby more firmly unite the cover and the book. In practice, however, it has been found that this preliminary roughening is not always sufficient for the purpose and that, if grooves are cut into the book-back preliminary to the application of the adhesive, the operation of attaching the cover to the book is facilitated. The object of this invention is to provide means for cutting grooves in the backs of books preliminary to attaching covers thereto.

With this object in view, the invention consists of a rotatable cutting member having a cutting surface of spiral formation for cutting a gradually deepening groove in the backs of books as they are successively passed over the cutter by a continuously moving conveyer located above it and carrying the books in an upright position with their backs lowermost, the upright axis of rotation of the cutting member being, at its upper end, slightly inclined from the vertical in a direction opposite to that in which the books move while they are being acted upon by the cutting member. The cutting member is so rotated as to initially

engage the book with the inner end of the spiral cutting surface so that the lateral deflection of the spiral while it is acting on the book is in the same direction as that of the travel of the book and the book is therefore initially engaged by the inner end of the spiral cutting surface. The relative speeds of the conveyer and the cutting member and the lateral deflection of the spiral are such that each revolution of the spiral produces one groove in the back of a book and there is substantially no displacement of the book and the cutting member while they are in engagement with each other.

In the particular embodiment of the invention chosen for illustration a spiral shaped groove cutting member is mounted on the upper end of a vertical shaft in position to engage books as they are carried past by the conveyer of a book covering machine.

In the accompanying drawings there is illustrated a preferred embodiment of the invention, but it is to be understood that the invention may be carried out by other embodiments and by mechanism widely different from that selected for illustration.

Figure 1 is an end elevation of a device embodying the invention and showing its relation to a book covering machine a part of which is shown in vertical transverse section.

Fig. 2 is a vertical longitudinal sectional view of the device with a diagrammatic showing of the relation of the books thereto.

Fig. 3 is a plan view of the groove cutting member and its support.

Fig. 4 is an enlarged sectional view of a detail taken along the broken line 4-4 of Fig. 3 and showing the specific relation of the cutting member and the book back.

The book covering machine disclosed is of the type in which the books are carried horizontally by the conveyer in a vertical position with their backs lowermost, and the path of travel of the books is such that the backs pass across the top of, and have transverse grooves cut therein by, the rotating spiral groove cutting member.

The groove cutting mechanism comprises a generally wheel-shaped member 1 having

an outer flange 2 which takes the form of a scroll, or spiral. The wheel-shaped member 1 is adapted to form a support for the groove cutting member 3 which is preferably made up of a plurality of flexible saw blades 4 removably mounted in a groove 5 in a face of the flange 2 and adapted to be held in place by means of the set screws 6. The wheel-shaped member 1 is adjustably mounted on the substantially vertical shaft 7 by means of the engagement of the clamping hub 8 with a threaded portion 9 of the shaft 7.

In the operation of the device a book 10 is carried by the clamp 11 of the continuously moving conveyer 12 across the upper face of the grooving device. As is best indicated in Fig. 2 of the drawing, the shaft 7 is inclined somewhat from the perpendicular in a direction toward the point from which the books advance so that the back of the book is engaged only by the high side of the groove cutting member. By this arrangement of the spiral groove cutting member the advance of the books is not interfered with by the engagement therewith of the opposite side of the cutter, and by rotating the groove cutting member at such a speed that the lateral deflection of the spiral 30 is equal to the travel of the books during the cutting of the groove, it will be seen that there is no relative movement of the book and the cutter in the direction of the path of travel of the book, and the action of the 35 groove cutting member is restricted to an area on the book back substantially equal to the width of the cutter, so that a clearly defined groove is produced with each revolution of the groove cutting member. Another 40 effect of tilting the vertical shaft 7 out of the perpendicular is to provide for the formation of the grooves with a gradually deepening cut. The rotation of the groove cutting member is in a counter-clockwise direction as viewed in Fig. 3 of the drawing and the end 13 of the cutter which initiates the cutting of the groove is at a lower level than the end 14 of the cutter which terminates the cutting of the groove. 45 It will be seen, therefore, that the grooving member gradually cuts deeper and deeper into the groove as it rotates.

The books 10 are so held in the clamps 11 that the back portions thereof project downwardly beyond the jaws of the clamps into a position where they can be acted upon by the groove cutting member, as shown in Fig. 1 of the drawing. A backing member 15 mounted on the framework of the machine 55 is adapted to engage the books and resist the tendency of the groove cutting member to distort the back of the book laterally. The backing member can be vertically adjusted to conform to the adjustment of the 60 groove cutting member which are made use

of in cutting grooves of different depths on books of different size.

The shaft 7 which carries the groove cutting member 3 is preferably continuously driven from a drive shaft 16 journaled in 70 the framework of the book covering machine 17. The speed of rotation of the groove cutting member is such that the rate of lateral deflection of the spiral is equal to the speed of travel of the books, as has been 75 pointed out, and, since both ends of the spiral cutter are on the same radial line, with each revolution of the groove cutting member the book travels a distance equal to the 80 radial distance between the ends 13 and 14 of the cutter. It will be seen that a groove is thus formed with each revolution of the cutter and that simultaneously with the withdrawal of the trailing end 14 of the cutter from one groove the foremost end 13 85 of the cutter is beginning the operation of cutting the next groove. The continued operation of the groove cutting member results in the formation of a series of grooves, one for each rotation of the member, across 90 the back of the book which are spaced apart a distance equal to the distance between the ends 13 and 14 of the cutter.

In order to convey motion from the drive shaft 16 to the cutter operating shaft 7, a 95 sprocket wheel 18 on the shaft 16 drives the sprocket 19 through the sprocket chain 20. The sprocket 19 is carried by a shaft 21 journaled in the framework 22 of the groove cutting device. A bevel gear 23 on the shaft 21 meshes with a bevel gear 24 on the shaft 7. Thus the drive shaft 16 drives the shaft 21 through the sprockets 18 and 19 and the sprocket chain 20, and the shaft 21 in turn 105 drives the groove cutting member through the engagement of the bevel gear 23 with the bevel gear 24.

What is claimed, is:

A groove cutting device for book covering machines comprising: a horizontally disposed book conveyer including clamps for supporting books, with their backs lowermost, in an upright position, a rotatable cutting member below the book conveyer, the upright axis of rotation of which is, at its upper end, slightly inclined from the vertical in a direction opposite to that in which the books move while being acted upon by said cutting member, a cutting surface of spiral formation with respect to said axis of rotation for producing a gradually deepening cut in the back of a book carried by said cutting member, means for so rotating said cutting member as to initially engage the book with the inner end of the spiral cutting 110 surface so that the lateral deflection of the spiral while it is acting on the book is in the same direction as that of the travel of the book, means for continuously moving the 115 book conveyer, the relative speeds of the 120 cutting member and the book conveyer being such as to provide a continuous series of grooves in the back of the book, and a backing member 125 mounted on the framework of the machine for engaging the book and resisting the tendency of the cutting member to distort the back of the book laterally, the 130 backing member being vertically adjustable to conform to the adjustment of the cutting member.

conveyer and the cutting member and the lateral deflection of the spiral being such that there is relatively no displacement, while in engagement, of the book and cutting member and such that each revolution of the spiral produces one groove in the back of a book.

Signed at New York city in the county of New York and State of New York this 25th day of October A. D. 1916.
